[57] CLAIM

The ornamental design for a stackable bottle rack, as shown and described.

DESCRIPTION

FIG. 1 is a perspective view of a stackable bottle rack showing our new design;

FIG. 2 is a top plan view thereof;

FIG. 3 is a bottom plan view thereof;

FIG. 4 is a front elevational view thereof; the rear being identical;

FIG. 5 is a side elevational view thereof; both sides being identical; and,

FIG. 6 is a perspective view thereof, the broken line showing of additional racks and bottles being for illustrative purposes only.

FIG. 1

FIG. 2

FIG. 2

FIG. 3

FIG. 4

FIG. 5
